UNITED STATES PATENT OFFICE.

HARRY VAN STELTEN, OF ARCO, MINNESOTA.

SHIPPING TAG.

Application filed April 6, 1923. Serial No. 630,262.

To all whom it may concern:

Be it known that I, HARRY VAN STELTEN, a citizen of the United States, residing at Arco, in the county of Lincoln, State of Minnesota, have invented certain new and useful Improvements in Shipping Tags; and I do hereby declare the following to be a full, clear, and exact description of the invention, such as will enable others skilled in the art to which it appertains to make and use the same.

This invention relates to new and useful improvements in tags, and particularly to tags used in shipping articles back and forth between two parties.

One object of the invention is to provide a tag of this character which includes means for shifting the names and addresses, or the addresses, of the sender and receiver, so that the handlers can readily ascertain to whom an article is consigned and from whom it was consigned.

Another object is to provide a device of this character which is simple in construction, easy and effective in operation, and which can be manufactured at a low cost.

Other objects and advantages will be apparent from the following description when taken in connection with the accompanying drawing.

In the drawing:

Figure 1 is a perspective view of a tag made in accordance with the invention.

Figure 2 is a horizontal longitudinal sectional view on the line 2—2 of Figure 1.

Figure 3 is a vertical longitudinal sectional view on the line 3—3 of Figure 2.

Referring particularly to the accompanying drawing, 10 represents the back plate of the tag, and 11 the front plate thereof, the latter being formed with a pair of longitudinal parallel slots 12. Disposed against the inner face of the front plate 11 is the movable address plate 13, the same being arranged to be slipped vertically to expose a different address through each opening or slot 12. Disposed longitudinally of the tag, and in front of the back plate 10, is a lever 14, the intermediate portion 40 of which carries a rivet 15, which is also secured to the center of the plate 13. Between the lever 14, and the plate 13, there is disposed a rectangular plate 16, the same being of the same width as the plates 10 and 11, but slightly shorter, one end of the plate 16 being disposed in alignment

with the plates 10 and 11, at one end and secured thereto by means of the rivets 17. The other end of the plate 16 is secured to the other ends of the plates 10 and 11, 60 inwardly of the end faces thereof, spacers 18 being disposed between the ends of the plate 16 and the plates 10 and 11, whereby to provide a working space for the lever 14, as clearly seen in the sectional views, 65 of the drawing. In the intermediate portion of the plate 16 there is formed a slot 19, which extends transversely of the plate, and receives slidably therethrough the rivet 15, of the lever 14, and the address plate 70 13. The other end of the lever 14 is formed with an elongated slot 20, which receives one of the rivets 17 therethrough, and whereby the lever is mounted for pivotal movement. The slot provides for the slight 75 longitudinal play of the plate 13, when the lever is swung on its pivot.

In one end of the back plate 10 there are formed two openings 21, with either one of which a similar opening 22, formed 80 in the adjacent end of the lever 14, is arranged to register to receive the wire or band of the seal 23, whereby to prevent movement of the plate 13.

Adjacent the upper slot 12 the word "To" 85 is printed, or otherwise formed on the front plate 11, while the word "From" is formed adjacent the other slot 12. On the front face of the plate 13 the address of the sender, and the address of the receiver, are 90 printed twice in alternate order, so that when the plate 13 is shifted downwardly the name of the receiver, and the address thereof, will appear in the upper slot 12, while the name and address of the sender 95 will appear in the lower slot. When the lever 14 is pushed upwardly the name and address of the original sender will appear in the upper slot, and the name and address of the receiver will appear in the lower slot. 100 Thus, an article may be shipped from a dealer to a purchaser, and the empty package returned to the dealer, and by shifting the plate 13, in the proper direction, the tag will show, in the first instance from the 105 dealer to the purchaser, and in the second instance, from the purchaser to the dealer.

The entire tag may be tacked to the article, or may be attached by a cord, as desired. The seal effectively prevents changing of the arrangement of the names and addresses of the dealer or sender, and the

receiver, or purchaser, while the article is in transit.

What is claimed is:

1. A shipping tag including a body having slots in one side, a plate slidably mounted on the body and having duplicated names and addresses thereon and visible through said slots in one order, and means for shifting the name and address plate to reverse the order in which the names and addresses appear through the slots.

2. A shipping tag including a body having a pair of slots, a plate slidably mounted on the first plate and having duplicated names and addresses arranged to appear through the slots, and a lever carried by the body and connected with the said plate for moving the second plate to display first one set of names and addresses and then the other set through the slots.

3. A shipping tag including a front and back plate, the front plate having longitudinal slots therein, a plate slidably mounted between the front and back plates and having a name and address for display through each of the slots, a lever pivotally

supported at one end between the front and back plates and having its intermediate portion pivotally connected with the slidable plate for moving the slidable plate to reverse the order in which the names and addresses appear through the slots, and means for locking the lever at each limit of its pivotal movement.

4. A shipping tag including a front and a back plate, the front plate having eight openings, a name and address plate slidable between the front and back plates, a lever for moving the address plate to alternate the display of the names and addresses through the eight openings, one end of the lever and the corresponding end of the back plate being formed with openings for the reception of a locking means for maintaining the slidable plate against movement.

In testimony whereof, I have affixed my signature in the presence of two witnesses.

HARRY VAN STELTEN.
